RETURN BEND FITTING

Clarence B. Harbison, Lima, Ohio, assignor to
 The Ohio Steel Foundry Company, Lima, Ohio,
 a corporation of Ohio

Application October 17, 1938, Serial No. 235,307

3 Claims. (Cl. 285—20)

This invention relates to improvements in return bend fittings for oil refineries, and more particularly to such return bends in which the two yokes of said fittings are made in separate pieces to permit individual replacement of the tube connected to either yoke without disturbing the companion yoke or attached parts.

The primary object of the present invention is the provision of simple and improved means for connecting together the separate yokes of a return bend of this class in a manner to prevent relative lateral twisting of the yokes or relative movements thereof axially of the connected tubes, and which at the same time permits easy and rapid assembly and connecting of the yokes in a tube bank.

Further objects and advantages of the invention will be apparent from the following detailed description and from the accompanying drawings, in which—

Figure 1 is an outer end view of a return bend embodying the invention with parts broken away and parts removed; Fig. 2 is a central longitudinal section thereof; Fig. 3 is a side elevation of one form of clamping means embodying the invention; Fig. 4 is a section on the line 4—4 in Fig. 3; Fig. 5 is a fragmentary view similar to Fig. 3 with the clamping means provided with one threaded stud; Fig. 6 is a view similar to Fig. 1 showing a slightly modified form of the clamping means with parts thereof broken away; Fig. 7 is a section on the line 7—7 in Fig. 6, and Fig. 8 is a side elevation of this modified form of clamping means.

In the embodiment of the invention illustrated in the drawings, 1, 1 designate the two separate yokes of a return bend adapted to be assembled in side by side relation and each having an opening 2 therein in which the end of a refinery still tube (not shown) may be suitably secured in parallel relation to its companion tube.

A U-bend member 4 connects the outer ends of the openings 2 of a pair of yokes and is held in seated engagement with the yokes in any suitable manner as well understood in the art. The manner of mounting and holding the U-bend member in engagement with the yokes forms no part of the present invention and need not be described.

Referring now to my improved clamping means for fastening a pair of yokes 1 together, and particularly to the form shown in Figs. 1 to 4, it will be noted that the adjacent or inner side of each yoke 1 is provided with a boss-like extension 10, preferably of rectangular form in cross section.

The adjacent faces 11 of these extensions are plain, or substantially so, and are disposed in spaced parallel relation when the yokes are properly assembled. At the inner and outer end edges of each extension 10 are formed opposing grooves 12 and 13, respectively. Each of these grooves is parallel to the adjacent margin of the respective face 11 and has its bottom surface inclined at an acute angle to said face so that each extension, in longitudinal section, is of dovetail form.

An insert 15 of substantially rectangular block form is removably disposed between the extensions 10 of an assembled yoke pair and coacts with the opposing faces 11 thereof to hold the yokes in proper spaced relation to suit the desired spacing of the connected tubes. These inserts have flat abutting engagement with the extension faces 11 and are free to have sliding movements in any direction parallel to said faces except for the clamping feature hereinafter described.

The insert 15, at its inner end, is provided with a cross-head 16 adapted to overlap the inclined walls of the grooves 12 of connected yokes and 25 having undercut inclined portions 17 for complementary wedging engagement with such walls. The insert 15, at its outer end, has one or more threaded studs 18 projecting therefrom in the major plane of the insert and through registering apertures in a clamping piece 19 which is similar in form to the cross-head 16. This clamping piece overhangs the inclined walls of grooves 13 of a yoke pair and has inclined portions 20 in complementary wedging engagement with said walls.

Nuts 21 are threaded on the stems 18 and cooperate therewith to draw the head 16 and clamp piece 19 of the insert into clamping coaction with the engaged extensions. It is apparent that the clamping of the extensions 10 in this manner is of a wedging nature tending to draw such extensions against the insert and to prevent relative movement of the yokes longitudinally of their openings.

In the present instance, the insert 15 has coaction with the extension faces 11 only at its corners, being provided for such purpose with the corner bearing portions 22. Also, the wedging portions 17 and 20 of the head 16 and clamping piece 19 are short lengthwise of said parts and coact with the extensions 10 at the end portions only of their respective edges. In Figs. 1-3, the insert is shown as having two threaded studs 18 and in Fig. 5 as having only one of such studs.

In the use of yoke clamping means of this character, it is important in practice to provide some means other than the opposed gripping or clamping action of the parts 16—19 against the extensions 10 to prevent lateral relative twisting actions of the engaged yoke pair, and such means should be operative for this purpose whether the yoke parts are held firmly by the clamping means against relative longitudinal movements or are loose to permit such movements to a limited extent. An important feature of the present invention for this purpose is the provision of angularly projecting lugs 25 on the ends of the clamping parts 16 and 19 to lap and engage the respective ends of the extensions 10. Each lug 25 is of sufficient width to span the adjacent ends of the insert 15 and to lap the respective ends or corner portions of the extensions 10 at the sides thereof which are longitudinal to the yokes 1. It is apparent that the wedging portions 17 and 20 of the clamping part 16 and 19 engage the upper and lower edges of the extensions 10 to draw the extensions together and tend to prevent relative longitudinal movements of the engaged yokes, while the lugs 25 engage the respective corner portions of the side edges of said extensions to prevent any relative lateral twisting movement of the yokes. The lugs 25 have sliding coaction with the sides of the extensions 10 longitudinally of the yokes so that they will effectively act to prevent any relative twisting movement of the yokes when the clamping means is either in tight or loose coaction with the extensions. In Figs. 6 and 7 of the drawings, the inner side extensions of the yoke members are designated 38 and are adapted to have their opposing faces drawn together in abutment. For this purpose the abutting faces of the extensions 10 are longitudinally recessed as shown at 31 to permit the stem clamping bolt 32 to extend therethrough. This stem is spaced from the side walls of the recesses 31 so that it does not in any way act to prevent relative lateral twisting movements of the yokes. The stem at its lower and upper ends is provided with a cross-head 33 and clamping piece 34 which are similar to the parts 16 and 19 of the form previously described and coact with the respective upper and lower inclined edge surfaces of the extensions 30 in a similar manner thereto to draw the yoke together and prevent relative longitudinal movements thereof. The parts 33 and 34 are also provided at their ends with lugs 35 which coact with the sides of the extensions 30 in the same manner that the lugs 25 coact with the sides of the extensions 10 of said previous form.

So far as the engagement of the clamping means with the extensions of an associated yoke pair is concerned, the action is similar to that of my prior Patent No. 1,862,748, issued June 14, 1932, and the present improvement of such patent resides primarily in the making of the clamping elements in such form and the provision of the end lugs thereon as to enable the clamping elements to coact with the side edges of the adjacent side extensions of the yokes to prevent relative lateral twisting action of the yokes without interfering with the clamping action or with any permissible relative longitudinal movement thereof should such movement be desired.

I wish it understood that my invention is not limited to any particular construction, arrangement or form of the parts as it is capable of numerous modifications and changes without departing from the spirit of the claims.

Having thus described my invention, what I claim as new and desire to secure by United States Letters Patent, is:

1. A return bend fitting, including a pair of separable yokes having confronting faces, and means to connect the yokes together including an intermediate plate-like member having a movable part interposed between and engageable with the confronting faces of the yokes to hold same in spaced relation, said yokes and member having complementary wedging parts, means to clamp the movable part of the spacing member onto the latter whereby to cause the wedging parts to effect movement of the yokes against the spacing member thereof to tightly clamp all of the parts together, and means carried by the connecting means and engaged with the yokes whereby to prevent lateral twisting of the yokes relative to each other.

2. A return bend fitting in accordance with claim 1, wherein the spacing member and the movable part thereof have lugs, which, extend across the line of separation of the yokes, and which overlap each of the adjacent side faces of the yokes, to prevent lateral twisting of the yokes relative to each other.

3. A return bend fitting including a pair of separable yokes having confronting faces, an inner member, and an outer member, said yokes and members having complementary parts which wedgingly engage each other, means to draw the members together and thereby the yokes, and means at each of the ends of the members extending across the line of separation thereof and overlapping each of the adjacent side faces of the yokes to prevent lateral twisting of the yokes relative to each other.

CLARENCE B. HARBISON.
